US00D505476S

(12) **United States Design Patent** (10) Patent No.: **US D505,476 S**
McGarry (45) Date of Patent: **** May 24, 2005**

(54) **PISTOL**

(75) Inventor: **James McGarry**, Prescott Valley, AZ (US)

(73) Assignee: **Sturm, Ruger & Company**, Southport, CT (US)

(**) Term: **14 Years**

(21) Appl. No.: **29/203,552**

(22) Filed: **Apr. 15, 2004**

(51) LOC (7) Cl. **22-01**

(52) U.S. Cl. **D22/104**

(58) Field of Search **D22/100, 104, D22/105, 108, 199; D21/567, 570, 573-575, 42/1.02, 7, 50, 65, 70.11, 71.02, 74, 75.03, 117, 22, 37, 40, 114, 84; 362/110, 113**

(57) **CLAIM**

The ornamental design for a pistol, as shown and described.

DESCRIPTION

FIG. 1 is a left side elevational view of a pistol showing my new design;

FIG. 2 is a right side elevational view thereof;

FIG. 3 is a top plan view thereof;

FIG. 4 is a bottom plan view thereof;

FIG. 5 is a front elevational view thereof; and,

FIG. 6 is a rear elevational view thereof.

All broken lines in the above figures are for illustrative purposes only and form no part of the claimed design.

1 Claim, 2 Drawing Sheets
